UNITED STATES PATENT OFFICE.

JAMES H. DENEFE, OF ST. LOUIS, MISSOURI.

IMPROVEMENT IN STOVE-LID LIFTERS.

Specification forming part of Letters Patent No. 128,792, dated July 9, 1872.

I, JAMES H. DENEFE, of St. Louis, in the county of St. Louis and State of Missouri, have invented certain Improvements in Stove-Lifters, of which the following is a specification:

Nature and Objects of the Invention.

The first part of my invention relates to the combination of stove-lifter, wrench, and poker, in such a manner that one instrument will answer for all three of the same; and consisting of a handle with the lifting-bar and wrench, and the poker attached to the same.

The figure in the drawing shows the combination and the article complete.

General Description.

The handle A is made of cast-iron or brass, and the poker B can be made from one-half inch rod-iron, prepared before casting the handle A, and cast in the handle. The handle A can

be made of a size suitable to the use for which it is intended, and has the lifting-bar C attached. The handle is of an oval shape, the slot H in the body of which forms the wrench. The poker B can be made the desired length, and of a size sufficient for the use for which it is intended.

Claim.

I claim as my invention—

The device A B C, as herein described, combining a lifting apparatus for stove-lids, a wrench, and shaker for stoves, grates, &c., and a fire-poker, arranged and combined as set forth.

JAMES H. DENEFE.
